UNITED STATES PATENT OFFICE.

ALFRED C. BARROW, OF LYNCHBURG, VIRGINIA, ASSIGNOR TO A. C. BARROW & COMPANY, OF LYNCHBURG, VIRGINIA, A CORPORATION OF VIRGINIA.

POCKET.

Application filed May 5, 1922. Serial No. 553,670.

To all whom it may concern:

Be it known that I, ALFRED C. BARROW, a citizen of the United States, residing at Lynchburg, in the county of Campbell and 5 State of Virginia, have invented certain new and useful Improvements in Pockets; and I do hereby declare the following to be a full, clear, and exact description of the invention, such as will enable others skilled in the 10 art to which it appertains to make and use the same.

This invention relates to improvements in overalls or work garments and more particularly to the provision of an improved pocket 15 therefor.

It is well known that the bottom of the pockets of work garments wear out very quickly due to the miscellaneous objects carried in the pockets and it is an object of the 20 invention to overcome this weakness by providing a reenforced pocket, such reenforcement preferably consisting of overlapped portions of the fabric constituting the pocket proper.

25 The various features of novelty of the invention will appear from the detailed description taken in connection with the accompanying drawings forming part of the specification.

30 Referring to the drawing,

Figure 1 is a view showing the two pieces from which the improved pocket is made;

Fig. 2 shows the two pieces overlapped and sewed at one of their ends;

35 Fig. 3 shows the pieces sewed up along their side edges to form a pocket, the pocket being shown inside out and having a supplemental patch pocket sewed to one of said pieces;

40 Fig. 4 shows the finished pocket ready for attachment to the overall;

Fig. 5 is a view looking down into the pocket, and

Fig. 6 is a perspective view illustrating 45 the application of the invention to an overall.

Referring to the drawings, 10 and 11 indicate the two pieces of which the pocket is made and 10' and 11' flaps or extensions on said pieces. The flaps 10' and 11' are placed 50 one over the other, and their edges *a*, *b* sewed to the pieces 11 and 10 respectively,

whereby a double thickness of fabric or reinforcement R is formed. Notches 12, 13 serve to indicate proper placement of said flaps, and also indicate the line on which the 55 pieces are turned in sewing up the sides of the fabric to make the pocket. Said notches also permit the bottom corners of the pocket to be sewed diagonally as indicated in Fig. 3.

Attached to the piece 10 is a fabric 15 of 60 the same texture as the body B of the overall and 16 indicates a supplemental patch pocket likewise sewed to said piece and also to the fabric 15, this arrangement being more or less conventional.

A pocket constructed as above described provides a double thickness of material at the bottom of the pocket in a manner which reduces the manufacturing operations to a very simple form. The pieces 10 and 11 are 70 the only two pieces of material required to make the reenforced pocket, thus avoiding the cutting of a separate reenforcement piece and the consequent handling and attachment of the same. By providing the extensions 10' and 11' on the main pieces 10 and 11 respectively, of the pockets, it is merely necessary to overlap said extensions and sew the two edges *a* and *b* of said extensions to the body portions 11 and 10 respectively. 80 As already indicated the notches 12 not only serve as markers for properly overlapping the extensions, but they also serve to indicate the bottom line of the pocket, the pieces 10 and 11 being turned on the 85 line joining the opposite notches. Said notches also enable the bottom corners of the pocket to be sewed diagonally, thus avoiding the objectional rectangular corners found in ordinary pockets.

90 What I claim is:

1. A pocket comprising two pieces of material overlapped and stitched together at one of their ends said pieces being provided with opposite disposed alined notches, the 95 side edges of said pieces being stitched together, said overlapped portion forming a reenforced bottom of said pocket.

2. A pocket comprising two pieces of material overlapped and sewed together at one of their ends, said pieces being turned midway of said overlapped portion and sewed 100

together along their adjacent side and bottom edges and also adjacent the bottom edge whereby a pocket with double bottom is formed.

5. The arrangement as in claim 2, characterized by each of said pieces having a pair on notches, one notch in each side edge, said

pieces being turned on the line forming said notches, the sides of said notches being sewed and constituting the bottom corners 10 of the pocket.

In testimony whereof I affix my signature.

ALFRED C. BARROW.
